CLAIM

The ornamental design for a pipette tip rack assembly, as shown and described.

DESCRIPTION

FIG. 1 is a top perspective view of a pipette tip rack assembly;

FIG. 2 is a front view thereof;

FIG. 3 is a back view thereof;

FIG. 4 is a side view thereof;

FIG. 5 is a side view thereof;

FIG. 6 is a top view thereof;

FIG. 7 is a bottom view thereof;

FIG. 8 is a bottom perspective view thereof;

FIG. 9 is an enlarged view of area 9 circled in FIG. 7;

FIG. 10 is an enlarged view of area 10 circled in FIG. 7;

FIG. 11 is an enlarged view of area 11 circled in FIG. 7; and,

FIG. 12 is an enlarged view of area 12 circled in FIG. 7.

The broken lines depict portions of the pipette tip rack assembly that form no part of the claimed design.
